UNITED STATES PATENT OFFICE.

ALBERT W. KERBER, OF SHARON, PENNSYLVANIA.

GLOBE-HOLDER.

No. 887,650.

Specification of Letters Patent.

Patented May 12, 1908.

Application filed January 5, 1907. Serial No. 350,925.

To all whom it may concern:

Be it known that I, ALBERT W. KERBER, citizen of the United States of America, residing at Sharon, in the county of Mercer and State of Pennsylvania, have invented certain new and useful Improvements in Globe-Holders, of which the following is a specification, reference being had therein to the accompanying drawing.

10 This invention relates to globe holders designed for chandeliers, lamp brackets and similar gas fixtures having suspended lamps and globes.

15 The object of this invention is to provide a simple and inexpensive globe holder that can be easily and quickly attached to a gas fixture.

20 Another object of this invention is to provide a globe holder for detachably holding globes, shades and similar vitreous gas fixtures.

25 A further object of this invention is to provide a strong and durable globe holder which will be inexpensive to manufacture.

30 With these and other objects in view which will more readily appear as the invention is better understood, the same consists in the novel construction, combination and arrangement of parts to be hereinafter more fully described and then specifically pointed out in the appended claims.

35 Referring to the drawing forming part of this specification, like numerals of reference designate corresponding parts throughout the several views, in which:

Figure 1 is a side elevation of my improved globe holder, Fig. 2 is a view in elevation of one of the hook-members used in connection with the same.

40 In the accompanying drawing, the reference numeral 1 designates a depending gas pipe forming a conducting or supply pipe for the light-producing element, and carrying a circular gas fixture or globe supporting bracket 2 of greater diameter than the supply pipe and arranged concentrically therewith, said fixture having a plurality of openings 3 formed therein. This type of fixture has been heretofore used in connection with 45 screws (not shown) for holding a globe 4, which is provided with a flared end 5 that fits within the fixture 2.

50 My invention resides in dispensing with the fastening means heretofore employed and providing a resilient circular clamp or holder for the flared edge 5 of the globe 4.

The holder or clamp comprises a ring 6 formed of a piece of wire or similar material and having its ends loosely connected together or abutting whereby the ring 6 can be expanded. Upon the ring is mounted a coiled spring 7 having its ends connected together as at 8. The convolutions of the spring are closely arranged whereby the same can be expanded upon the ring 6. The ring 6 and the spring 7 are suspended from the fixture 2 by hook-members 9, the wire 6 passing through the eye 10 of said members, while said hook-ends thereof are engaged in the openings 3 of the fixture 2. I preferably 70 use four hook-members for supporting the holder or clamp in a horizontal position beneath the fixture 2 and it is obvious that a greater number of hook-members can readily be used.

75 To place the globe 4 in position, the flared end 5 is partly inserted in the holder or clamp and then said holder or clamp expanded to permit of the flared end passing upwardly towards the fixture 2 and immediately upon 80 said end reaching its destination, the contraction of the holder or clamp firmly retains the globe in proper position.

85 As shown, the hook members 9 are of sufficient length to permit the globe-clamping device (the spring and ring) to be located below and in parallel planes with the bracket, thereby providing a space between the globe and its coil and the bracket. Hence, the globe is not only detachably connected to the 90 bracket, but the coil, being spaced from said bracket and connected therewith only by the hooks, is substantially free from heat-conducting contact therewith. Furthermore, the coil, being located on the outer surface 95 of the globe and under tension with its individual coils spaced apart, what heat is conducted by the globe is rapidly dissipated so that at no time is the coil spring kept in a highly heated condition. And inasmuch as 100 the spring and globe are spaced from the bracket, permitting heat from within the globe to pass out through the space therebetween, but in a direction where the spring will not be subjected to the direct action of 105 the heat, the structure is such as to be especially advantageous for use in connection with gas fixtures for certain classes of incandescent burners, the structure permitting of a maximum supply of air or rapid egress of 110 heat without requiring the use of a heavy globe supporting device, the spring coil be-

ing sufficient to support the globe when not placed in position where it becomes heated to a high degree.

As shown, the bracket 2 and the globe-clamping member are of similar contour and have approximately the same diameter, thereby simply suspending the globe from the bracket. Owing to this construction the hooks need not be carefully adjusted to position nor need be so formed as to provide a relatively non-yielding connection between the bracket and the clamping member.

From the foregoing description it will be observed that I have devised a simple holder comprising very few parts which can be easily and quickly assembled and placed in engagement with various kinds of gas fixtures.

I do not care to confine myself to the size, proportion and minor details of construction as such changes as are permissible by the appended claims may be resorted to without departing from the spirit and scope of the invention.

What I claim and desire to secure by Letters Patent, is:-

1. The combination with a globe-supporting bracket carried by a supply-pipe, of a spring globe-clamping member, and means loosely carried by said member for detachably securing said member below said bracket and spaced therefrom.

2. The combination with a globe-supporting bracket carried by a supply-pipe, of a spring globe-clamping member, and means loosely carried by said member for detachably securing said member below said bracket and spaced therefrom, said means comprising a plurality of hook-members carried by the globe-clamping member and hav-

ing an open hook at their free ends to permit engagement with the bracket.

3. In combination, a globe-supporting bracket carried by a supply pipe and having a plurality of apertures, a globe having an inwardly-directed annular depression adjacent its top, a resilient clamping-member mounted within said depression, and a plurality of hooks loosely carried by said member and having their free ends formed for engagement with the apertures of the bracket, the hooks being of a length to permit the clamping member to lie in a plane parallel with and below the bracket.

4. The combination with a globe-supporting bracket carried by a supply pipe and provided with a plurality of apertures, of a globe-securing clamp comprising a ring, a coil spring arranged on said ring, said spring and ring being clamped around the globe, and a plurality of hook-members having eyes in one end receiving said ring and hooks on their outer ends to engage in the apertures in said bracket.

5. The combination with a globe-supporting bracket carried by a supply pipe, of a globe-holder comprising a ring, a coil spring surrounding said ring, said spring and ring forming a carrier for the globe, and a plurality of hook-members loosely mounted on the ring and having their outer ends formed with hooks for detachable engagement with the bracket.

In testimony whereof I affix my signature in the presence of two witnesses.

ALBERT W. KERBER.
